Des. 189,824
Patented Feb. 28, 1961

189,824

SHOE RACK

David Harper, 2122 Webster Ave., Pittsburgh, Pa.

Filed Sept. 18, 1959, Ser. No. 57,607

Term of patent 14 years

(Cl. D33—3)

FIG. 1.

FIG. 2.

FIG. 3.

FIG. 4.

Figure 1 is a perspective view of a shoe rack showing my new design;

Figure 2 is a top plan view of the shoe rack design illustrated in Figure 1;

Figure 3 is a front elevational view of the shoe rack; and,

Figure 4 is a side elevational view of said shoe rack. I claim:

The ornamental design for a shoe rack, as shown.
